UNITED STATES PATENT OFFICE.

HARLEY E. ANDERSON, OF CHICAGO, ILLINOIS, ASSIGNOR OF ONE-HALF TO WILLIAM L. KELLOGG, OF GLEN ELLYN, ILLINOIS.

BRAKE MECHANISM.

Application filed November 12, 1924. Serial No. 749,370.

This invention relates to brake mechanisms.

One object of the invention is to provide a brake mechanism especially applicable to 5 railway cars in which means are provided for rapidly taking up the slack in the brake rigging, and thereafter upon an increased resistance being encountered, to automatically bring about the operation of means for 10 greatly multiplying the power applied to the brake rigging.

A further object of the invention is to provide a power multiplying mechanism including lever means adapted to normally remain 15 in inoperative position during one phase of operation of the device, the parts of such device being arranged in such a manner that the pivotal point of the lever means in one position is disposed between the actuating portion of the lever means and the brake applying means and in a plane common therewith so that the force on said lever means is exerted longitudinally thereof with 20 no tendency to swing the lever means on its pivot until the same is otherwise released.

A further object of the invention is to provide mechanism for controlling the retention, or release, of the lever means, the operation of such mechanism being dependent 25 upon means which are affected by an increased resistance, to automatically release said lever means to effect a great multiplication in power, and which serves to return the lever means to its inoperative position 30 when the force exerted upon the mechanism is relieved, together with means which positively prevent swinging movement of the lever tending to release the same.

A further object of the invention is to 35 provide lever means which are especially constructed to resist twisting strains, such means including a plurality of levers pivotally mounted in spaced relation, and having their actuating portions connected together, 40 in conjunction with means upon the fulcrum portions of said levers, which are arranged to simultaneously engage suitable fulcrum locations.

Still another object of the invention is to 45 provide a novel mounting for a device of this character which comprises a track together with means upon the traveling portion of the mechanism which engage the track,

whereby the mechanism is bodily movable along the same, such track also providing 55 means for the engagement of the lever means to afford fulcrum locations therefor.

Other objects and advantages will more clearly and fully appear from the description and claims hereinafter following.

In the drawings forming a part of this specification, Fig. 1 illustrates diagrammatically a railway car, including the ordinary brake rigging, and showing my invention interposed in such rigging. Fig. 2 is 60 an enlarged top plan view of the invention showing the same detached from the car. Fig. 3 is a side elevation of the invention showing the same in its normal inoperative position. Fig. 4 is a longitudinal, partly 65 sectional, partly elevational view, of the invention, having portions omitted to show the interior mechanism, and showing the lever means in normal inoperative position. Fig. 5 is a view similar to Fig. 4, having portions 70 omitted to expose the arrangement of parts, the released operative position of the lever means being indicated in dotted lines. Fig. 6 is a bottom plan view of the invention, the parts being in the positions illustrated in 75 Fig. 4. Fig. 7 is a transverse, sectional view of the invention on the line 7—7 of Fig. 3. And Fig. 8 is a transverse, sectional view of the invention on the line 8—8 of Fig. 3.

Referring to the drawings, 10 denotes a 80 portion of a railway car including a brake winding mast 11, brake rigging 12, air brake 13 and equalizer bar 14, my invention being shown as interposed in the brake rigging, and indicated generally by the letter A.

Such invention broadly includes a support B having a rack C thereon; a yoke D having a slidable connection with said support, lever means E carried by said yoke and adapted to cooperate with the rack C, lever supporting and centering means F, resilient means G normally holding the parts in inoperative position, and auxiliary means H, for preventing swinging movement of the lever means E.

The support B preferably comprises an elongated member having a vertically extending center rib 20, on the upper edge of which at spaced intervals are provided securing plates 21 and 22, the plates 21 having apertures 23 extending therethrough and

through the support B, and the plate 22 being provided with a slot 24 extending through the plate at one side thereof. The lower portion of the support is provided with laterally extending flanges 25—25 providing a track upon which the multiplying mechanism is slidably mounted as will be herein-after described.

The support B is adapted to be secured to a bracket 26 upon the underside of the car, in a position suitably located with reference to the brake rigging 12. Such support is preferably secured to the bracket 26 by means of bolts 27 which extend through the apertures 23, and have suitable nuts threaded thereon. A bolt 28 also extends through the slot 24 in the securing plate 22, such bolt terminating beneath the furcations provided by the slotted portion 24 of such plate, and having a nut threaded thereon and bearing against the under sides of such furcations, this manner of securing the plate 22 being for the purpose of preventing the extension of the bolt entirely through the support so as not to interfere with the rack C provided on the under surface thereof. The rack C comprises a plurality of transversely disposed teeth preferably formed integrally on the under side of the support B, such rack preferably extending from a point slightly to one side of the intermediate securing plate 21 in the direction of the plate 22, to the end of the support B, as clearly shown in Figs. 4 to 6 inclusive.

The power multiplying means which cooperates with the rack C, preferably includes a carrier member in the form of the yoke D, and upon such yoke are extensions 29, which have inwardly turned hooked portions 30 provided with spaced ribs 31—31 adapted to engage the opposite sides of the related flanges 25—25 of the support B, such construction permitting longitudinal bodily movement of the yoke D along the support, the arrangement being such that the yoke travels in a straight line and is held against lateral swinging or vertical displacement.

The free ends of the yoke D are provided with bearings to accommodate a pivot pin 32, upon which is swingably mounted the lever means E. Such means preferably comprises a pair of spaced levers 33, having hubs 33^a pivotally mounted on the pin 32 and held in spaced relation by a connecting web forming part of mechanism herein-after referred to, the actuating portions 34 of such levers extending inwardly between the furcations of the yoke D, and being pivotally connected together by means of a pin 35. Pivotally mounted upon the pin 35 is one end of a link 36, such link being curved as shown, and the opposite end thereof having an eye 37 connected to the portion 38 of the brake rigging 12, leading to the brake mast 11. The levers 34 are provided with ful-

crum portions, preferably in the form of mutilated gears 39, which in one position of the parts as hereinafter explained cooperate with the teeth upon the rack C.

The lever means supporting mechanism 70 preferably comprises a U-shaped or forked supporting member 40, disposed between the furcations of the yoke D, and the portions 34 of the levers 33, the bight 41 of such U-shaped portion having a block 42 preferably formed integral with the inner end thereof as shown. Such block preferably has a recess 43 therein for the reception of an enlargement 44 formed on the end of a stem 45, the outer end of such stem extending through a block 42^a, preferably formed integral with the end of the yoke D, such stem having an eye 46, connected to the chain 47 of the brake rigging, which in turn is connected to the equalizer bar 14 having connection with the brake shoes in the ordinary manner. An expansible spring 48 is disposed about the block 42 and the block 42^a, as clearly shown in Figs. 4 to 6, for the purpose of normally holding such blocks in spaced relation.

The outer end portions of the legs of the U-shaped member 40 are provided with centrally disposed semi-circular openings 49, adapted to normally fit about the hubs 33^a 95 of the levers 33, and outwardly inclined wedge portions 50 are provided on such end portions on opposite sides of the openings 49, which are arranged to cooperate with wedge portions 51 formed on the lever hubs. By this arrangement the spring 48 presses the U-member 40 toward the pivot pin 32, so that the openings 49 and wedge portions 50 and 51 serve to retain the lever means in inoperative position.

Independent additional means are provided for supporting such lever means in inoperative position. Such means include a hooked portion 52 formed between the levers 33, and extending rearwardly between the levers 33, such means serving to hold such levers in spaced relation. The hooked portion 52 is normally engaged by a gravity actuated dog 54 pivotally mounted upon a pivot pin 55 provided on the U-shaped member 40, such dog having a stop 56 adapted to engage the top edges of the U-shaped member to prevent too great swinging movement in an anti-clockwise manner and a stop 57 to prevent too great swinging of such dog 120 in clockwise direction.

The operation of the device is as follows: Upon rotation of the brake staff 11 the initial tension upon the portion 38 of the brake rigging is transmitted to the outer end of the link 36, thence to the inner ends of the levers 34, which bear upon the pivot pin 32 mounted on the ends of the yoke D. The yoke D in turn transmits such power to the resilient means 48 which bears against 130

the block 42, so that the power is transmitted to the connecting member 45, and thence to the brake chain 47. This initial tension causes the power multiplying mechanism to move bodily along the track 25-25, the spring resistance offered by the means 48 being sufficient to prevent release of the lever means until the slack has been completely taken up. When the slack has been taken up, upon continued rotation of the brake staff 11, the tension upon the yoke D is sufficient to compress the spring 48 which results in the hubs 33^a of the levers moving out of the openings 49 in the U-shaped member 40. This relative movement of the yoke D and the U-member 40 also serves to draw the hooked portion 52 of the lever means from engagement with the dog 54, so that the lever means are free to move downwardly, which causes the actuating portions 34 of the levers to swing outwardly bringing about the engagement of the fulcrum portions 39 of the levers with the rack C, as shown in Fig. 5 resulting in a great increase in power. Upon release of the brakes, through the action of the spring 48, the lever means E are drawn toward the U-shaped member, and by reason of the engagement of the wedge portions 50 on the hubs 33^a of the lever with the wedge portions 51 on the ends of the U-shaped member, the lever means are centered with respect to the openings 49. During this movement the dog 54 is displaced upwardly until the same drops into engagement beneath the hooked portion 52, as in its original position.

It should be particularly observed that by reason of the construction described the power exerted upon the lever means is in a straight line longitudinally thereof, that is, the line of force extends from the actuating ends of the lever means through the pivot of such lever means, to the source of power, so that there is no tendency of the lever means to turn about its pivot and so prematurely release the power multiplying means. Through this arrangement in conjunction with the spring 48, and the wedge portions 50 and 51, is sufficient to prevent premature swinging movement of the lever means, for the sake of safety, I preferably provide the auxiliary means H which positively prevent the lever means assuming operative position until the spring 48 has been fully compressed. It should also be particularly observed that due to the provision of the spaced levers, and the spaced fulcrum ends thereof, engaging the rack C in spaced relation, all tendency of such levers to twist, because of the relatively great power applied thereto, is fully counteracted.

I have herein shown and described what I now consider the preferred manner of carrying out my invention, but the same is

merely illustrative, and I contemplate all changes and modifications that come within the scope of the claims appended hereto.

I claim:

1. In a brake rigging, the combination with a power mechanism connected thereto; of power multiplying means associated with said mechanism, including lever means having an actuating portion normally extending to one side of its pivot, and a source of power at the other side of said pivot and connected to the actuating portion of said lever, said actuating portion, pivot and source of power being disposed in a common plane during one phase of operation. 70 75 80

2. In a brake rigging, the combination with a power mechanism connected thereto; of power multiplying means associated with said mechanism, including lever means having an actuating portion normally extending to one side of its pivot, and a source of power at the other side of said pivot and connected to the actuating portion of said lever, whereby the force exerted by said source of power passes in a straight line 90 through the pivot of said lever means; and means for releasing said lever means from its normal inactive position to operate said power multiplying means. 85

3. In a brake rigging, the combination with a power mechanism connected thereto; of power multiplying means associated with said mechanism, including lever means having an actuating portion normally extending to one side of its pivot, and a source of power at the other side of said pivot and connected to the actuating portion of said lever, whereby the line of force exerted by said source of power passes through the pivot of said lever means; means for releasing said lever means from its normal inactive position to operate said power multiplying means; and means for returning said lever means to normally inactive position. 95 100 105

4. In a brake rigging, the combination with a power mechanism connected thereto; of power multiplying means associated with said mechanism, including lever means having an actuating portion normally extending to one side of its pivot; a source of power at the other side of said pivot connected to the actuating portion of said lever means whereby the line of force exerted thereby passes through the pivot of said lever means; and means operated by a predetermined resistance for releasing said lever means from its normal inactive position to operate said power multiplying means. 110 115 120

5. In a brake rigging, the combination with a power mechanism connected thereto; of power multiplying means associated with said mechanism, including lever means having an actuating portion normally extending to one side of its pivot; a source of 125 130

power at the other side of said pivot connected to the actuating portion of said lever means whereby the line of force exerted thereby passes through the pivot of said lever means; means operated by increased resistance for releasing said lever means from its normal inactive position to operate said power multiplying means; and means for returning said lever means to normally inactive position.

6. In a brake rigging, the combination with a power mechanism connected thereto; of power multiplying means associated with said mechanism including lever means having an actuating portion normally extending to one side of its pivot; means for supporting said lever means in inactive position; means for releasing lever means; and a source of power at the other side of said pivot connected to the actuating portion of said lever means whereby the line of force exerted thereby passes through the pivot of said lever means.

7. In a brake rigging, the combination with a power mechanism connected thereto; of power multiplying means associated with said mechanism, including lever means having an actuating portion normally extending to one side of its pivot; means for supporting said lever means and being movable relatively thereto for releasing said lever means; and a source of power at the other side of the pivot of said lever means connected to the actuating portion thereof, whereby the line of force exerted thereby passes through the pivot of said lever means.

8. In a brake rigging, the combination with a power mechanism connected thereto; of power multiplying means associated with said mechanism including lever means; means for supporting said lever means at one point thereon, said supporting means being movable relatively to said lever means to release the same; and independent means for holding said lever means in inactive position during movement of said supporting means from supporting position.

9. In a brake rigging, the combination with a power mechanism connected thereto; of power multiplying means associated with said mechanism including lever means; means for supporting said lever means at one point thereon, said supporting means being movable relatively to said lever means to release the same; independent means for holding said lever means in inactive position during movement of said supporting means from supporting position; and means operable by a predetermined resistance for controlling the relative movement of said supporting means and said lever means.

10. In a brake rigging, the combination with a power mechanism connected therewith; of power multiplying means associated with said mechanism including

pivoted lever means; means for supporting said lever means operable by predetermined resistance to release the same; and means for retaining said lever means inactive until said lever means are clear of said supporting means.

11. In a brake rigging, the combination with a power mechanism connected thereto; of power multiplying means associated with said mechanism, including swingable lever means; a source of power spaced from said lever means and connected with the actuating portions thereof, the body portion of said lever means being disposed in the line of force exerted by said source of power upon the actuating portion of said lever means.

12. In a brake rigging, the combination with a power mechanism connected thereto; of power multiplying means associated with said mechanism, including swingable lever means; a source of power spaced from said lever means and connected with the actuating portion thereof, the body portion of said lever means being disposed in the line of force exerted by said source of power upon the actuating portion of said lever means; and means operable by variable resistance for releasing said lever means in one phase of operation, and for returning the same to inactive position during another phase of operation.

13. In a brake rigging, the combination with a power mechanism, connected therewith; of power multiplying means associated with said mechanism, including pivoted lever means movable with reference to said power mechanism to release the same; and means free of said pivot for retaining said lever means in inactive position during the movement tending to release the same.

14. In a brake rigging, the combination with a power mechanism connected therewith; of power multiplying means associated with said mechanism, including lever means having an actuating portion normally extending to one side of its pivot; means for supporting said lever means in inactive position, said means being movable with reference to said lever means to release the same; a source of power at the other side of said pivot connected to the actuating portion of said lever means whereby the line of force exerted thereby passes through the pivot of said lever means; and independent means for supporting said lever means in inactive position during its movement to released position.

15. In a brake rigging, the combination with a power mechanism, connected therewith; of power multiplying means associated with said mechanism, including lever means movable with reference to said power mechanism to release the same; means for

- retaining said lever means in inactive position during the movement tending to release the same; means for returning said lever means to inactive position, and means independent of said retaining means for positioning said lever means upon its return to inactive position.
16. In a brake rigging, the combination with power mechanism connected therewith; of power multiplying means associated with said mechanism, including lever means movable with reference to said power mechanism to release the same; independent means for positively supporting said lever means in inactive position during the movement tending to release the same; and means for returning said lever means to inactive position, said means including a device for guiding said lever means with respect to said supporting means.
17. In a brake rigging, the combination with a power mechanism connected therewith; of power multiplying means associated with said mechanism, including lever means comprising a plurality of spaced lever elements providing fulcrum portions.
18. In a brake rigging, the combination with power mechanism connected therewith; of power multiplying means associated with said mechanism, including lever means comprising a plurality of spaced levers having their actuating portions connected together and providing a plurality of spaced fulcrum portions.
19. In a brake rigging, the combination with a power mechanism connected therewith; of power multiplying means associated with said mechanism including lever means comprising a plurality of spaced levers having their actuating portions connected together and normally extending to one side of the pivots of said levers; and a source of power at the other side of said pivot connected to the actuating portions of said lever means, whereby the line of force exerted thereby passes through the pivot of said lever means.
20. In a brake rigging, the combination with a power mechanism connected therewith; of power multiplying means associated with said mechanism including lever means; a source of power connected with the actuating portion of said lever means; and means for preventing twisting of said lever means during operative movements thereof, said means including elements for bracing said lever means against lateral stresses throughout its extent.
21. In a brake rigging, the combination with power multiplying mechanism connected therewith; of power multiplying means associated with said mechanism including lever means comprising a plurality of spaced levers, the actuating portions of said levers extending to one side of the pivots thereof; a link connected to the actuating portions of said levers, and extending to the other side of said pivots; and a source of power connected to said link.
22. In a brake rigging, the combination with power multiplying mechanism connected therewith; of power multiplying means associated with said mechanism including lever means comprising a plurality of spaced levers, the actuating portions of said levers extending to one side of the pivots thereof; a link connected to the actuating portions of said levers, and extending to a point beyond the pivot of said lever means; and a source of power connected to said link being foldable between said levers.
23. In a brake rigging, the combination with power multiplying mechanism connected therewith; of power multiplying means associated with said mechanism including lever means comprising a plurality of spaced levers, the actuating portions of said levers extending to one side of the pivots thereof; a link connected to the actuating portions of said levers and extending to a point beyond the pivots; a source of power connected to said link; and means operable by a predetermined resistance for releasing said lever means.
24. In a brake rigging, the combination with a power mechanism connected therewith; of power multiplying means including swingable lever means in the form of a plurality of levers having their actuating portions connected, and having fulcrum portions disposed in spaced relation; a source of power connected with the actuating portions of said lever means, and spaced therefrom, the body portions of said lever means being normally disposed along the line of force exerted by said source of power on the actuating portions of said lever means.
25. In a brake rigging, the combination with a power mechanism connected therewith; of power multiplying means including swingable lever means in the form of a plurality of levers having their actuating portions connected, and having fulcrum portions disposed in spaced relation; a source of power connected with the actuating portions of said lever means, and spaced therefrom, the body portions of said lever means being normally disposed along the line of force exerted by said source of power on the actuating portions of said lever means; and means operable by a variable resistance for controlling the movement of said lever means.
26. In a brake rigging, the combination with a power mechanism associated therewith; of a support having means providing a plurality of fulcrum locations; a carrier movably mounted on said support; lever means swingably mounted on said carrier, said lever means having an actuating por-

tion connected to a source of power, and having fulcrum portions co-operating in one position with said fulcrum locations; a supporting member mounted on said carrier and connected to one end of said brake rigging, said support having means for the detachable reception of said lever means, said lever means being normally held in position whereby the body portion of such lever means is disposed along the line of force from said source of power to the actuating portion of said lever means; and resilient means interposed between said carrier and said supporting member.

27. In a brake rigging, the combination with a power mechanism associated therewith; of a support having means providing a plurality of fulcrum locations; of a carrier movably mounted on said support; lever means swingably mounted on said carrier, said lever means having actuating portions connected to one end of said brake rigging, and having spaced fulcrum portions arranged in one position to cooperate with said fulcrum locations; a supporting member mounted on said carrier, and connected with the other end of said brake rigging, said support having means for retaining said lever means in inoperative position; and resilient means interposed between said carrier and said support.

28. In a brake rigging, the combination with a power mechanism associated therewith; of a support having means providing a plurality of fulcrum locations; of a carrier movably mounted on said support; lever means swingably mounted on said carrier, said lever means having actuating portions connected to one end of said brake rigging, and having spaced fulcrum portions arranged in one position to cooperate with said fulcrum locations; a supporting member mounted on said carrier, and connected with the other end of said brake rigging, said support having means for retaining said lever means in inoperative position; and resilient means interposed between said carrier and said support, said supporting means being provided with wedge portions cooperating with wedge portions upon said lever means for positioning said lever means with reference to said supporting member.

29. In a brake rigging, the combination with a power mechanism connected therewith; of a support having means providing a plurality of fulcrum locations; a carrier movably mounted on said support; lever means swingably mounted upon said carrier, said lever means having its actuating portions connected with one end of said brake

rigging, and having fulcrum portions arranged to cooperate with said fulcrum locations in certain positions; a supporting member connected to the other end of said brake rigging; resilient means interposed between said carrier and said supporting member; and means for retaining said lever means in inoperative position during relative movement of said carrier and said supporting means, said retaining means being in the form of a pivoted dog and a cooperating hooked member.

30. In a brake rigging, the combination with a power mechanism connected therewith; of a support having means providing a plurality of fulcrum locations; a carrier movably mounted on said support; a plurality of spaced levers pivotally mounted on said carrier, said levers having the actuating portions connected, said spaced levers providing a plurality of fulcrum portions cooperable with said fulcrum locations in certain positions of the parts; a source of power spaced from said actuating portion and connected thereto, the body portions of said levers being disposed along the line of force exerted by said source of power upon the actuating portions of said levers; a supporting member mounted on said carrier and connected to the other end of said brake rigging, said supporting member being provided with means for the reception of portions of said levers, said supporting means also having wedge portions cooperating with wedge portions on said levers for positioning said levers with respect to said supporting member; and means for retaining said lever means inactive during certain relative movements of said support and said carrier, said means being in the form of a pivoted dog and a cooperating hooked portion.

31. In a brake rigging, the combination with a power mechanism; of a support having laterally disposed flanges providing a track; of a carrier provided with hooked portions having means slidably mounted on the flanges of said track; lever means pivotally mounted on said carrier and connected to one end of said brake rigging; a supporting member connected to the other end of said brake rigging and having means adapted to retain said lever means in inoperative position; and resilient means interposed between said carrier and said supporting member.

In witness that I claim the foregoing I have hereunto subscribed my name this 7th day of November, 1924.

HARLEY E. ANDERSON.
